DEMODULATOR

Loy E. Barton, Collingswood, N. J., assignor to
 Radio Corporation of America, a corporation
 of Delaware

Application October 28, 1933, Serial No. 695,555

7 Claims. (Cl. 250—27)

My invention relates to demodulators and it has particular relation to the utilization of diodes as demodulators in radio receivers.

There are many advantages accruing from the use of a diode as a detector in a radio receiver. Such advantages are well known to those skilled in that art.

If a diode is provided with an output circuit constituted by a leak-resistor and a radio frequency by-pass condenser and the said output circuit is coupled to the input terminals of an audio-frequency amplifier tube in the manner referred to above, distortion will occur when incoming signals have high percentage modulation. Such distortion is occasioned by the fact that the total impedance of the leak and the shunting network to audio frequency currents is less than the ohmic resistance of the diode leak to the direct current resulting from rectification of the carrier. It is, accordingly, an object of my invention to provide a diode-utilization network that shall permit the demodulation, without distortion, of a carrier wave having high percentage modulation.

Another object of my invention is to provide an improved method of utilizing a multi-electrode thermionic tube for the combined functions of demodulation and audio-frequency amplification.

As mentioned above, distortion occurs when a carrier wave having high percentage modulation is demodulated in a diode that is coupled to an amplifier through a resistor-condenser network for the reason that the impedance of the network to audio frequency currents is less than its resistance to direct currents. This condition provides an audio frequency path to ground which, by reason of the audio frequency potentials developed tends to pass more peak current than is available from the rectified carrier wave, with the result that the potentials impressed upon the input of the audio frequency amplifier tube are not truly representative of the modulation. In order, therefore, to make certain that the current requirements of the system may be met, I impress upon the input circuit of the diode, through a resistor, additional potential derived either from the common anode supply source for the receiver or from a separate battery. Such additional potential makes available the direct current needed to take care of high percentage

modulated carriers and the potentials impressed upon the amplifier tube are not distorted.

The novel features that I consider characteristic of my invention are set forth with particularity in the appended claims. The invention itself, however, both as to its organization and its method of operation, together with additional objects and advantages thereof, will best be understood from the following description of a specific embodiment, when read in connection with the accompanying drawing, in which

Fig. 1 is a diagrammatic view of a portion of a radio receiver of the superheterodyne type including a preferred embodiment of my invention;

Fig. 2 is a graph exemplifying the manner in which my invention obviates distortion, and

Fig. 3 is a graph exemplifying certain diode characteristics.

Although my invention is applicable to resistance-condenser networks of known types for the purpose of coupling a diode to an audio frequency amplifier, I prefer to illustrate it in connection with a double diode-pentode tube, wherein demodulation of an incoming carrier wave, audio-frequency amplification of the demodulated signal, and the derivation of automatic volume control potentials are simultaneously accomplished.

In practicing my invention, referring to Figure 1 of the drawing, I prefer to utilize a thermionic tube of the combined double diode-pentode type. This tube is provided with two diode plates 1 and 3, a common equi-potential cathode 5, a control grid 7, a screen grid 9, a suppressor grid 11, and an anode 13.

Incoming modulated signals at an intermediate frequency are impressed between the diode plate 1 and the cathode of the tube, over a circuit including the tuned secondary of an intermediate frequency transformer 15, a leak constituted by a plurality of resistors R₁ and R₂, series connected, the first resistor being shunted by an audio frequency and radio frequency by-pass condenser C₁ and the second resistor also having a shunting radio frequency by-pass condenser C₂.

The output circuit of the tube includes the field winding L₁ of a loudspeaker 16, a potential

source exemplified in the drawing by a rectifier 17, a tuning-indicator lamp 18, and the primary winding of an audio frequency transformer 19. An audio frequency by-pass condenser C_4 is connected in shunt to the rectifier and the field winding.

Incoming signals impressed between the diode plate 1 and the cathode of the tube are rectified therein and give rise to a direct current (I) in the leaks R_1 and R_2 , which current has an average value proportional to the amplitude of the carrier and has an audio frequency component the amplitude of which is proportional to the percentage modulation of the said carrier. The control grid 1 of the tube is connected through a resistor R_4 to the movable contact element 20 of a potentiometer device, one end of the resistor element R_6 of which is directly connected to the junction between the leaks R_1 and R_2 and the other end of which is connected to the cathode of the tube through a stopping condenser C_3 .

The direct current (I) derived from the intermediate frequency carrier appears across the leaks R_1 and R_2 , and the bias applied to the control grid 1 of the tube depends upon the ratio between the two diode leak resistors. The amplitude of the audio frequency potentials impressed upon the control grid is determined by the setting of the movable element 20 of the potentiometer. The audio frequency current is shunted across R_1 by the condenser C_1 , so that the control grid 1 may receive full grid swing at low percentage modulation.

If the diode condenser C_2 has a very high impedance to audio frequency compared to the ohmic resistance of the resistors R_1 and R_2 , disregarding, for the moment, the fact that the condenser C_1 has low impedance to audio frequency currents, and the presence of the potentiometer and the stopping condenser C_3 , the impedance of the resistors R_1 and R_2 , from the end farthest from the cathode to the cathode is the same for audio frequencies as for direct current.

Assuming, as mentioned above, that the rectified carrier current has an average value represented by (I) and is flowing through the resistors, the voltage (D. C.) across the said resistors is $(I)(R_1+R_2)$ and, if 100% modulation exists, the voltage across the resistors will decrease to zero and increase to $2(I)(R_1+R_2)$ during a complete audio cycle. This means that the peak audio voltage component of the current under the given conditions is equal to $(I)(R_1+R_2)$.

Now, assume that the parallel paths constituted by R_5 , C_3 , and C_4 are added in order that the demodulated signal may be impressed upon the grid 1 of the amplifier portion of the tube and that the said parallel paths for audio frequency have approximately one-half the impedance of the resistor R_2 . In such event, the total audio frequency impedance to ground is substantially $33\frac{1}{3}\%$ of (R_1+R_2) . The direct current voltage across (R_1+R_2) is still $(I)(R_1+R_2)$ and at $33\frac{1}{3}\%$ modulation the peak audio frequency voltage component of the direct current is equal to

$$\frac{(I)(R_1+R_2)}{(3)}$$

If this voltage is applied across the total impedance to ground having a value of

$$\frac{(R_1+R_2)}{(3)}$$

a peak audio frequency current will flow in the

network equal to (I), which causes the rectified current in resistors R_1 and R_2 to go from zero to $2(I)$ during an audio cycle, thus impressing, through the potentiometer contact element 20 and the resistor R_4 , undistorted audio frequency potentials upon the control grid 1 of the pentode portion of the tube.

Now, if the incoming carrier wave is 66 2/3% modulated, the audio frequency potentials appearing across the resistors R_2 and R_5 necessitate the flow of an average diode current of substantially $2(I)$ in the complete network. This condition, referring to Figure 2 of the drawing, reduces the average diode current (I) to zero early in the negative part of the audio frequency potential cycle and the current is thereafter cut off until the instantaneous value of the audio frequency current requirement is not greater than (I). This causes distortion on all carriers having more than $33\frac{1}{3}\%$ modulation.

It can also be shown that, if the modulation is 100%, substantially three times the average current normally available must flow in the diode if distortion is to be obviated.

According to my invention, therefore, I connect the end of the resistor R_1 nearest the diode plate to the anode potential source 17 through a variable high resistor R_6 . This resistor, preferably, has a maximum resistance of the order of 5 megohms, which is so high that the total impedance of the diode coupling network to audio frequency currents is substantially unaffected.

The increased diode current provided by the connection just referred to only increases the actual diode voltage by a very small amount. That is, referring to Fig. 3 of the drawing, if the normal diode current is (I_0) without the additional direct current potential, a current three times as large, indicated by the point I' , causes the positive potential on the diode plate to only increase a trifle. Therefore, the detector efficiency is decreased by a negligible amount if the incoming carrier wave has a normal amplitude of several volts.

It should also be apparent, from the drawing, that the amplitude of the signal impressed upon the control grid from the diode portion of the tube depends upon the position of the contact element 20. Movement of the element 20, to control volume, has no effect upon the bias applied to the grid since, as before stated, this depends only upon the ratio of R_1 to R_2 .

From the foregoing description of a preferred embodiment of my invention, it will be apparent that the system may be adjusted to handle, without distortion, signals having modulation percentage in excess of $33\frac{1}{3}\%$.

The amount of extra current supplied to the diode is determined by the resistor R_6 and the potential of the source 17. The adjustment of the resistor R_6 determines the percentage modulation which may be efficiently handled, but in general the added current should be sufficient to prevent distortion with 100% modulation.

It will be noted, from the drawing, that a connection extends from the diode plate 3 through resistors R_7 and R_8 to ground, through which potential may be applied between the diode plate 3 and the common cathode 5 of the tube. This provides automatic volume control potentials for preceding amplifier tubes in the system, analogous to the system disclosed and claimed in my co-pending application, Serial No. 640,946, filed November 3, 1932, and assigned to Radio Corporation of America. Since the provision of

such potentials is an incidental part of the present invention, no further description is necessary.

In a receiver as actually constructed by me according to Figure 1 of the drawing, the several components have the following values:

R₅—1 megohm

L₁—5000 ohms

R₆—5 megohms

10 R₄—40,000 ohms

R₁—.5 megohm

R₂—.5 megohm

C₁—.05 mfd.

C₂—.0002 mfd.

15 C₃—.5 mfd.

C₄—10 mfd.

R₇—50,000 ohms

R₈—1 megohm

C₅—.01 mfd.

20 As hereinbefore pointed out, through practicing my invention, I am able to utilize a diode for the demodulation of high percentage modulated carrier waves and to impress them, through a network having low impedance to audio frequencies, upon subsequent devices, such as the input terminals of an amplifier tube, or a loudspeaker, without distortion.

25 Although I have disclosed my invention in connection with a single multi-electrode tube, it is not limited to the specific tube shown and it is, of course, also applicable to receivers wherein the diode and audio frequency amplifier tubes are physically separate and distinct.

30 Many other modifications will be apparent to those skilled in the construction and operation of radio receiver devices. My invention, therefore, is not to be limited except insofar as is necessitated by the prior art and by the spirit of the appended claims.

35 I claim as my invention:

1. In combination, a modulated signal input circuit, means providing a diode rectifier in connection with said circuit, an output impedance in series with said rectifier and connected with 40 the cathode thereof, volume control means connected in shunt with at least a portion of said output impedance, an electric discharge amplifier associated with said diode rectifier and having an input grid connection with said volume 45 control means and having a conductive connection therethrough to said output impedance, and means for applying a positive potential to the anode end of said diode output impedance.

50 2. In combination, a modulated signal input circuit, means providing a diode rectifier in connection with said circuit, an output impedance in series with said rectifier and connected with the cathode thereof, potentiometer means connected in shunt with at least a portion of said output 55 impedance, an electric discharge amplifier associated with said diode rectifier and having an input grid connection with said potentiometer means and having a conductive connection therethrough to said output impedance means for applying a positive potential from one of the amplifier electrodes to said diode output impedance adjacent to the anode end thereof, and means for varying said potential.

3. In combination, a thermionic tube of the multi-electrode type having a cathode, a control grid, and a plate constituting an amplifier and being provided with a plate which, in conjunction with the said cathode, is adapted to function as a demodulator of the diode type, a connection between the diode plate and the cathode including a resistor-capacitor network, a connection from the network to the control grid, and means for supplying unidirectional positive potential to the anode of the demodulator with respect to its cathode, whereby distortion is prevented in the event that carrier waves having high percentage modulation are impressed upon the tube between the diode plate and the cathode thereof.

4. The invention set forth in claim 3 characterized in that the impedance of the resistor-capacitor network to currents at audio-frequencies is less than its direct current resistance.

5. The invention set forth in claim 3 characterized in that the resistor capacitor network includes a resistor connected conductively between the diode plate and the cathode of the tube and a second resistor and capacitor serially connected in shunt relation to the first mentioned resistor and further characterized in that the impedance of the entire network to currents at audio frequencies is less than the direct current resistance of the said first mentioned resistor.

6. In combination, a thermionic tube having a cathode, a control grid and a plate constituting an amplifier and being provided with an additional plate which, in conjunction with the cathode, is adapted to function as a demodulator of the diode type, an input circuit for the diode portion of the tube including a leak resistor, a capacitor having relatively high impedance to currents at audio-frequencies connected in between a point on the leak resistor and the cathode, a capacitor having relatively low impedance to currents at audio frequencies connected in shunt to the remainder of the leak resistor, a capacitor having low impedance to currents at audio frequencies and a coupling resistor serially connected between the aforementioned point on the leak resistor and the cathode and a variable connection between the coupling resistor and the control grid whereby maximum grid-swing may be obtained during the demodulation of carrier currents having low percentage modulation.

7. In combination, a modulated signal input circuit, means providing a diode rectifier in connection with said circuit, an output impedance in series with said rectifier and connected with the cathode thereof, potentiometer means connected in shunt with a portion of said output impedance adjacent to the cathode end thereof, an electric discharge amplifier associated with said diode rectifier and having an input grid connection with said potentiometer means and a conductive grid connection therethrough to said output impedance, and means for supplying current at a unidirectional positive potential to the anode end of said diode output impedance with respect to the cathode end thereof.

LOY E. BARTON.
